UNITED STATES PATENT OFFICE.

MARTIN V. RUSH, OF ANDERSON, INDIANA.

LADDER-BRACKET.

1,112,660.

Specification of Letters Patent.

Patented Oct. 6, 1914.

Application filed March 25, 1914. Serial No. 827,170.

To all whom it may concern:

Be it known that I, MARTIN V. RUSH, a citizen of the United States, residing at Anderson, in the county of Madison and State of Indiana, have invented a new and useful Ladder-Bracket, of which the following is a specification.

This invention relates to improvements in ladder brackets.

10 An object of the present invention is to provide a bracket for the support of scaffolds, such as used by painters, carpenters, etc., which may be used with ladders with different rung spacings.

15 A further object is to provide a bracket including an upstanding strut member which can be maintained in a vertical position although the ladder upon which it is secured may not be so disposed.

20 A further object is to provide a bracket which will be of simple construction and therefore cheap to manufacture and which will be capable of supporting scaffolding thereabove or by reversing the relative positions of the two parts of the bracket, the scaffolding may be supported therebeneath, the bracket being then in, what is termed, a depending position.

With the foregoing and other objects in view which will appear as the description 30 proceeds, the invention resides in the combination and arrangement of parts and in the details of construction hereinafter described and claimed, it being understood that 35 changes in the precise embodiment of the invention herein disclosed, can be made within the scope of what is claimed, without departing from the spirit of the invention.

In the drawings accompanying this specification and forming part thereof, the preferred embodiment of my invention has been shown, wherein:—

Figure 1 is a view in perspective of my improved ladder bracket; Fig. 2 is a front 45 view in elevation, disclosing the adaptability of the bracket to maintain the lower strut member in a vertical position when the ladder is not so disposed. Fig. 3 is a top plan view thereof. Fig. 4 is a diagrammatic 50 view illustrating the bracket in its depending position.

Referring to the drawings in which similar reference numerals designate corresponding parts throughout the several views, the

bracket includes the strut 5 to which are 55 pivotally secured the plank supporting members 6. The bracket herein disclosed may be used for various purposes but is particularly adapted for use with a ladder such as disclosed in the drawings, which includes 60 the stiles 7 and the rungs 8.

The strut 5 is preferably formed of a wide thin strip of metal with the lower end twisted through 90 degrees as illustrated at 65 9 to thus provide a wide bearing surface for the pivotal connection with the plank supporting member 6 and also with the cross arms 10. A plurality of the cross arms 10 are provided and are riveted secured to the strut 5, it being noted that in each case 70 a single rivet is used and the said rivet is so driven in place that a movable joint will be effected between said strut member and the arm 10.

The outer extremities of the arms 10 are 75 offset as at 11 to thus provide an outstanding ledge against which the S-shaped hooks 12 are secured. The said S-shaped hooks are rigidly secured to the arms 10 and are adapted to engage the ladder rungs as 80 clearly illustrated in Fig. 1. The said hooks are spaced a suitable distance apart, thus insuring the stability of the entire device.

The plank supporting members 6 are bent 85 intermediate their ends as at 13, the portions between the bend 13 and the pivotal joint with the strut 5 being designed to hold a plank or scaffolding in a level position and prevent the same from shifting. The 90 inner extremities of the plank supporting members 6 are bent outwardly as at 14. In order to strengthen the fork-shaped member so provided, a cross bar 15 is rigidly secured to the extremities of the forked portion as 95 clearly apparent in Fig. 3. Suitable hooks 17 are secured to the cross bar 15 and the ends of the fork 14—14 and are adapted to engage the rungs of a ladder as disclosed in Fig. 4.

100 The movable connection between the arms 10 and the strut 5 allows the strut to be placed in a vertical position, even though the ladder be slightly inclined to the vertical as illustrated in Fig. 2. The upper ladder 105 gripping portion 14—14, 16, 17 of the cross plank supporting member is pressed down by the upper rung 8 by reason of the fact

that the cross members 6 are formed of such material that they may twist about their longitudinal axes.

Having thus fully described my invention, what I claim is:—

1. A ladder bracket comprising a strut member inclined at an angle to the vertical taken at one plane, said strut twisted intermediate its ends, a plurality of arms pivotally secured to the lower extremity thereof, S-shaped hooks rigidly secured to the extremities of said arms, a supporting member pivotally secured to the remote extremity of said strut, the remote extremity of said supporting member provided with oppositely extending ends, a cross bar extending between said ends, and hooks rigidly secured to said brace bar.

2. A ladder bracket comprising a strut member twisted intermediate its ends through substantially 90 degrees, arms pivoted to the lower extremity of said member and provided with outstanding ledges at their extremities, S-shaped hooks rigidly secured to said arms and abutting said ledges, a supporting member pivotally secured to the remote extremity of said strut, said supporting member bent intermediate its ends, the portion between the bend and the pivotal connection with the strut adapted to receive a plank thereon and to prevent the shifting thereof, the bent member pivot-

ally secured to the remote extremity of said supporting member, the extremities of the supporting member and bend extending in opposite directions, and hooks rigidly secured to the forked end of the supporting member.

3. A ladder bracket comprising a strut member inclined at an angle to the plane of the ladder, a plurality of arms pivotally secured to the lower extremity of said strut member, S-shaped hooks secured to the extremities of said arms, a supporting member pivotally secured to the remote extremity of said strut, the remote extremity of said supporting member provided with means for detachably engaging a ladder.

4. A ladder bracket comprising a strut member, a plurality of arms secured to the lower extremity thereof, S-shaped hooks secured to the extremities of said arms, a supporting member pivotally secured to the remote extremity of said strut, and means carried at the remote extremity of said supporting member adapted to detachably engage a ladder.

In testimony that I claim the foregoing as my own, I have hereto affixed my signature in the presence of two witnesses.

MARTIN V. RUSH.
